Primary Examiner — George D. Kirschbaum*Assistant Examiner* — Suzanne E Tisdell(74) *Attorney, Agent, or Firm* — Sheppard Mullin Richter & Hampton LLP(57) **CLAIM**

The ornamental design for a portable power station, as shown and described.

DESCRIPTION

FIG. 1 is a top, front and right-side perspective view of a portable power station showing our new design;

FIG. 2 is a top, front and left-side perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines in FIGS. 1 through 8 depict parts of the portable power station that form no part of the claimed design.

1 Claim, 8 Drawing Sheets(56)
